[57] CLAIM

The ornamental design for baby booties, as shown and
described.

DESCRIPTION

FIG. 1 is a perspective view of a baby bootie, showing my
new design;

FIG. 2 is a top plan view thereof;

FIG. 3 is a left side elevational view, the right side being a
mirror image thereof;

FIG. 4 is a front elevational view thereof;

FIG. 5 is a rear elevational view thereof; and,

FIG. 6 is a bottom plan view thereof.

The broken line showing of the remainder of a baby bootie
is for illustrative purposes only and forms no part of the
claimed design.
